UNITED STATES PATENT OFFICE.

THOMAS M. BARBEE AND SAMUEL P. VOGT, OF CORYDON, INDIANA.

DESIGN FOR A STOVE.

SPECIFICATION forming part of Design No. 37,121, dated September 6, 1904.

Application filed April 2, 1904. Serial No. 201,349. Term of patent 14 years.

To all whom it may concern:

Be it known that we, THOMAS M. BARBEE and SAMUEL P. VOGT, citizens of the United States, residing at Corydon, in the county of Harrison and State of Indiana, have invented a new, original, and ornamental Design for Stoves, as disclosed in the accompanying drawing, which is a perspective view.

What we claim as new, and desire to secure by Letters Patent, is—

The ornamental design for a stove as shown.

THOMAS M. BARBEE.

SAM. P. VOGT.
